UNITED STATES PATENT OFFICE.

EDWARD J. WEIDNER, OF LINDSAY, NEBRASKA.

HUSKING-MACHINE.

No. 845,599.

Specification of Letters Patent.

Patented Feb. 26, 1907.

Application filed February 18, 1905. Serial No. 246,289.

To all whom it may concern:

Be it known that I, EDWARD J. WEIDNER, a citizen of the United States, residing at Lindsay, in the county of Platte and State of Nebraska, have invented new and useful Improvements in Husking-Machines, of which the following is a specification.

My invention has relation to a corn-husking apparatus, and it comprises two similar snapping-rolls of substantially equal diameters, each formed square in cross-section and with its periphery presenting four substantially equal plain faces joining at right angles, said rolls being equally geared directly together, so as to revolve in opposite directions with a feed motion at equal speeds, and being so correlated that each roll directly opposes one of its angles to one of the faces of the other roll, whereby a nipping action with a quick release is exerted upon the material fed between the rolls.

The invention will be hereinafter fully described, claimed, and illustrated in the accompanying drawings, wherein—

Figure 1 is a top plan view of my combined stripping and husking rolls arranged in relative position. Fig. 2 is a detail perspective view of one of the rolls. Fig. 3 is a sectional view on the line 3-3, Fig. 1, illustrating the angle or edge of one roll being in opposition to the plane surface of the other roll; and Fig. 4 is a view similar to Fig. 3.

Referring to the drawings by reference-numerals, 1 and 2 designate rolls squared in cross-section throughout their entire lengths and provided at their opposite ends with pin-tles 3, by means of which the rolls may be journaled in applied position upon a machine. These rolls are adapted to be arranged in parallelism and each has secured to one of its pin-tles 3 a gear 4, said gears being adapted to mesh, whereby to impart reverse rotary motion to the rolls. The rolls are so relatively geared that the angle or edge of one roll op-

poses the plane face of the other roll, as is 45 fully illustrated in Figs. 3 and 4 of the drawings.

It is apparent from the above description, taken in connection with the accompanying drawings, that during the rotation of the 50 rolls 1 and 2 the angle or edge of one roll will engage a stalk and impinge it between itself and the opposing plane face of the other roll, thereby carrying said stalk between the rolls and removing the ears therefrom. A further 55 rotation of the rolls will bring another angle into engagement with the husk of the ear and impinge the husk between itself and another plane face of the opposing roll and thereby remove the husk from the ear. During this 60 operation of removing the ear from the stalk and the husk from the ear the ear is not injured in the least, owing to the peculiar construction and relative arrangement of the 65 rolls.

Having thus fully described the invention, what is claimed as new is—

In a corn-husking machine, the combination of two similar snapping-rolls of substantially equal diameters, each formed square 70 in cross-section, and with its periphery presenting four substantially equal plain faces joining at right angles, said rolls being equally geared directly together so as to revolve in opposite directions, with a feed motion, at 75 equal speeds, and being so correlated that each roll directly opposes one of its angles to one of the faces of the other roll, whereby a nipping action with a quick release is exerted upon the material fed between the rolls, sub- 80 stantially as specified.

In testimony whereof I affix my signature in presence of two witnesses.

EDWARD J. WEIDNER.
